(57) **CLAIM**

The ornamental design for a dental oven as shown and described.

DESCRIPTION

FIG. 1 is a front perspective view of a dental oven, showing our new design.

FIG. 2 is a front perspective view of a dental oven, shown in a condition of use, for clarity of disclosure.

FIG. 3 is a right side elevation view of a dental oven.

FIG. 4 is a left side elevation view thereof.

FIG. 5 is a top plan view thereof.

FIG. 6 is a bottom plan view thereof.

FIG. 7 is a front elevation view thereof; and,

FIG. 8 is a rear elevation view thereof.

The broken lines in the drawings depict portions of the dental oven and form no part of the claimed design.

1 Claim, 8 Drawing Sheets
